TAPE PRINTER

Jacob H. Drillick, Brooklyn, N. Y.

Application October 17, 1950, Serial No. 190,600

8 Claims. (Cl. 178—4)

1

This invention relates to tape printing and more particularly is concerned with a method and apparatus by which printing on a single tape may be accomplished at a considerably greater rate than has heretofore been possible. For instance, tape printers have heretofore not generally been capable of printing at a rate in excess of 500 characters per minute. By employing my method and apparatus, however, characters may be readily printed on a single tape at a rate of from 1000 to 2000 per minute.

Tape printing has a great many applications the best known of which perhaps are in telegraphy and the transmission of stock quotations. In both applications, whether the message to be transmitted comprises a series of words only, or stock quotations, the message is first printed on a tape, by the sender, in the form of a series of perforations. This perforated tape is passed through a transmitter which, in response to the perforations on the tape, sends the message in the form of electrical or radio impulses to a receiver. The receiver may be, and in some cases is, the distributor of a teleprinter which distributes the impulses to operating parts of the teleprinter which then translates them into printed characters on a tape which is passed therethrough. In other cases the receiver includes a re-perforator, that is, a second tape is perforated in response to the impulses sent out by the transmitter. This perforated tape at the receiving station is then fed into a teleprinter which operates in response to the perforations in the tape to print the message upon a tape passing through it. In many cases the sender's perforator and transmitter are combined, but this equipment forms no part of my invention.

In the above system, and in all the systems with which I am familiar and which are now in use, the limitation with respect to speed, or rate, of printing characters on a tape is in the teleprinter, the transmitting and receiving apparatus being capable of operating at much greater speeds. The object of my invention is, therefore, a method of tape printing and a tape printing apparatus whereby a message, which may now be transmitted and received at a much greater rate than that at which the present teleprinters are capable of operating, may be transposed into a printed message on a single tape as fast as it is received.

Accordingly, my invention contemplates the use of a plurality of teleprinters through which a single tape, upon which the message is to be printed, is passed in series, each teleprinter serving to print a portion of the characters of the

2

message. The series of incoming consecutive signals is divided into a plurality of complementary series of signals, each complementary series being stored and conveyed at the proper time to an individual teleprinter which operates in response thereto. The teleprinters are synchronized in operation so that the totality of characters imprinted on the single tape, passing in series through them, in response to the complementary series of signals fed to each teleprinter, for a single consecutive series of characters, which constitutes the message, corresponds in order to the original undivided series of incoming consecutive signals. The only modification in a standard teleprinter that is essential in order that it may be employed in my method and apparatus is in its tape advancing mechanism, for it will be clear that if the characters are to be imprinted on a single tape at a much increased rate the tape will necessarily have to be moved through the teleprinters at a correspondingly increased rate. For instance if two teleprinters are used to imprint characters on a single tape which is passed through them in series it will be clear that the tape must necessarily be passed through the teleprinters at twice the normal rate. If the teleprinters are of the type in which the tape to be printed is passed through in a stepping motion, then all that needs to be done to adapt them to use in my method and apparatus is to increase the size of the increment of advance, or step, maintaining the incremental or step frequency the same. Thus in using two teleprinters, the size of the step or increment of advance is doubled, thereby doubling the linear speed of the tape through the teleprinters.

While, as stated previously, my invention may be employed with a number of different type teleprinters, for instance those which print in response to a series of electrical or radio impulses or those which print in response to a series of perforations in a perforated tape, a specific embodiment of the invention employing the latter type will be hereafter described. For this purpose reference may be made to the accompanying drawing in which:

Figure 1 is a diagrammatic representation of the elements of the specific embodiment of my invention, and

Figure 2 is a further diagrammatic representation of two teleprinters through which a perforated coded tape and the single tape upon which the message is to be printed are passed in series.

In Figure 1 a sending printer-perforator 10 is illustrated by which a message to be sent is

translated into a series of perforations on a tape 11. The perforated tape 11 is passed automatically to a transmitter 12 which translates the message contained on the tape into electrical or radio impulses. These impulses are transmitted over a line L to a receiver and re-perforator 13 which prepares a coded perforated tape 14 very much similar to tape 11. Tape 14 is then passed in series through a pair of teleprinters 15 and 16 which imprints the message represented by 10 perforations on the coded tape onto a single tape 17 passing in series through them.

Referring now to Figure 2, the dividing into complementary series of the series of consecutive signals on the coded tape and the operation of the teleprinters 15 and 16 will be described. While some teleprinters print upon a continuously moving tape, for simplicity, those illustrated are of the type in which the printed tape is passed through by a stepping motion. Whereas, in such teleprinters the printed tape is normally advanced step by step each step being one space, the teleprinters illustrated are modified to advance the printed tape in steps of two spaces. Were three teleprinters used the steps would be 25 three spaces each, etc. It is contemplated that the coded tape upon which the characters are stored will be advanced in synchronism with the printed tape, its advance also being in steps of two spaces each, each space containing one row of perforations representing one signal. The advancing means for the coded tape are illustrated diagrammatically as sprockets 15' and 16'. The advancing means for the printed tape are not 30 illustrated but are well-known and therefore need not be once it is understood that these means are modified to advance this tape in steps of two spaces rather than in steps of one space. The frequency of the step advances of both tapes is of course that which is normal for the teleprinters.

Each of the teleprinters 15 and 16 is also provided with a pick-up head 15'' and 16'', whereby the signals represented by perforations on the coded tape 14 are picked up and fed to the printing mechanisms of the teleprinters. They are 45 also only illustrated diagrammatically because there are a number of different types any of which may be employed.

For purposes of explanation the signals represented by transverse rows of perforations in tape 14 will be considered in pairs, for example pair 20 and pair 21. For simplicity the imprinting of but one word Good on printed tape 17 by 50 teleprinters 15 and 16 will be described. The pair 20 of signals includes the rows of perforations corresponding respectively to G and O and the pair 21 includes the rows of perforations corresponding respectively to O and D. The coded tape 14 is stepped through the teleprinters so 55 that the first row of perforations of any pair will, when the tape is stationary, be located opposite pick-up head 15'' of teleprinter 15 and the second row of perforations of a preceding pair will be located opposite pick-up head 16'' of teleprinter 16. Means (not shown) are also provided in each teleprinter for de-activation of its pick-up head during movement of the tape. Thus, despite the fact that all of the transverse rows of 60 perforations in the coded tape will pass under each pick-up head, the pick-up heads will only be operative to respond to one row of each pair, the head 15'' responding to the first row of each pair and the head 16'' responding, subsequently, to the second row of that pair. Thus, in translating 65

the word Good from the rows of perforations representing it on the coded tape 14 to imprinted characters on the printed tape 17, the teleprinter 15 serves (in two steppings of the tapes) to imprint the G and the second O leaving a blank space therebetween. When both tapes subsequently have been advanced to the proper positions in teleprinter 16 this teleprinter will print the first O of the word in the space left between the G and O printed by teleprinter 15 and then will imprint the last letter D of the word.

Normally, both start and stop signals are sent through a teleprinting system, and a teleprinter upon receipt of the stop signal will cease to operate. It will thus be apparent that some provision must be made to keep receiver and perforator 13 and teleprinter 15 in operation at least to keep advancing the coded tape, and in the case of teleprinter 15 both the coded tape 14 and the printed tape 17, until the last character of the message has been imprinted on the tape 17 by teleprinter 16. To effect this, a stop control 22 is provided on printer 10 whereby all of the elements of the apparatus will be maintained in operation for the purpose of advancing the tapes a specified and predetermined number of steps after completion of the message. Thus if, for instance, the teleprinters 15 and 16 imprint characters on the printed tape ten spaces apart, control button 22 will maintain advance of the tapes for ten spaces at the end of a message so that teleprinter 16 may complete the printing of the end of the message on tape 17. Where a number of messages are being sent consecutively and without appreciable lapses of time therebetween the use of control button 22 will be obviated, it being intended for use only after the sending of one message when a subsequent message is not to follow in a reasonable time.

If, as suggested in the preamble of the specification, the teleprinters to be used operate in direct response to the impulses sent out by transmitter 12, the re-perforation feature of receiver 13 may be dispensed with and in its place may be substituted apparatus, for instance a series of stepping relays, whereby the impulses are divided into complementary series, one series being sent to teleprinter 15 and the other stored and conveyed at the proper time to teleprinter 16. With the provision of proper synchronizing means for the teleprinters the same results may be obtained as obtained by the above specifically described apparatus.

While two teleprinters have been included in the specific embodiment of my invention discussed, and described above, it will be understood that three or more may be employed provided corresponding modifications are made in the tape advancing means and the location of the pick-up head of each. Thus messages may be printed on a single tape by the method of my invention and by my apparatus at rates of 2, 3 or more times that which can now be accomplished by one teleprinter. Furthermore, it is to be understood that there are many modifications which may be made in the apparatus of my invention but it is intended that the invention should not be limited except to the extent set forth in the appended claims.

I claim:

1. In apparatus for printing a message upon a single tape in response to a series of consecutive signals corresponding to consecutive characters of the message, means for dividing said signals into two or more complementary series of spaced signal groups, a separate teleprinter corresponding

to each of said complementary signal series and responsive thereto, a single tape for receiving printed characters, said tape being adapted to pass through said teleprinters in series, and means for synchronizing the operation of said teleprinters so that the totality of characters imprinted on said tape forms a single consecutive series corresponding in order to the original series of consecutive signals.

2. Apparatus in accordance with claim 1 which includes means for advancing said tape through the teleprinters in series.

3. In apparatus for printing a message upon a single tape in response to a series of consecutive signals corresponding to consecutive characters of the message, means for dividing said series of signals into a plurality of complementary series, a teleprinter corresponding to each of said complementary series of signals and responsive thereto, a single tape for receiving printed characters, said tape passing through the teleprinters in series and having printed thereon by each teleprinter those characters of the message corresponding to the signals of the complementary series controlling the teleprinter, and means for advancing the tape through the teleprinters so that the first teleprinter imprints a character corresponding to one signal of its operating complementary series and then leaves sufficient blank space on the tape before imprinting the character corresponding to the next subsequent signal of its controlling complementary series so that the other teleprinters may subsequently imprint thereon in said space the characters corresponding to corresponding signals of their complementary series.

4. Apparatus in accordance with claim 3 which includes control means for operating the tape advancing means of all the teleprinters until the character corresponding to the last signal of the complementary series controlling the last teleprinter through which the tape passes has been printed, whereby the advance of the tape and printing thereon by the teleprinters is not discontinued until the complete message has been printed.

5. Apparatus in accordance with claim 3 which includes means for advancing the tape through

the teleprinters at a speed which is the product of the number of teleprinters and the speed at which it would be advanced through a single teleprinter if that teleprinter were printing the entire message.

6. Apparatus in accordance with claim 3 which includes means for synchronizing the operation of said teleprinters so that each is operated at the same time and so that the totality of characters imprinted on said tape forms a single consecutive series corresponding in order to the original series of consecutive signals.

7. In apparatus for printing a message upon a single tape in response to a series of consecutive signals corresponding to consecutive characters of the message, means for dividing said signals into two or more complementary series of spaced signal groups, a separate teleprinter corresponding to each of said complementary signal series and responsive thereto, a single tape for receiving printed characters, means for advancing said tape through the teleprinters in series until the last teleprinter has imprinted the character thereon corresponding to the last signal of the complementary series to which said last teleprinter is responsive, and means for synchronizing the operation of said teleprinters so that the totality of characters imprinted on said tape forms a single consecutive series corresponding in order to the original series of consecutive signals.

8. Apparatus in accordance with claim 7 which includes means for advancing the tape through the teleprinters at a linear speed which is equal to the product of the number of teleprinters and the linear speed at which it would be advanced through a single teleprinter if that teleprinter were printing the entire message.
